UNITED STATES PATENT OFFICE.

DORA AMELIA SCHWEIKER, OF LOS ANGELES, CALIFORNIA.

DESIGN FOR A PILLOW.

Application filed January 25, 1926. Serial No. 16,259. Term of patent 3½ years.

To all whom it may concern:

Be it known that I, DORA AMELIA SCHWEIKER, a citizen of the United States, residing at Los Angeles, in the county of Los Angeles and State of California, have invented a new, original, and ornamental Design for a Pillow, of which the following is a specification, reference being had to the accompanying drawings, in which—

Fig. 1 is a perspective view from the front;

Fig. 2 is a perspective view from the rear;
Fig. 3 is a side elevation.

I claim:—

The ornamental design for a pillow, substantially as shown.

DORA AMELIA SCHWEIKER.
